DESIGN FOR A TRACTOR HOUSING

Henry Dreyfuss, New York, N. Y., and Theophilus Brown, Moline, Ill., assignors to Deere & Company, Moline, Ill., a corporation of Illinois

Application March 26, 1945, Serial No. 118,720

Term of patent 14 years

(Cl. D14—3)

To all whom it may concern:

Be it known that we, Henry Dreyfuss and Theophilus Brown, citizens of the United States, residing at New York city, in the county of New York and State of New York, and at Moline, in the county of Rock Island and State of Illinois, respectively, have invented a new, original, and ornamental Design for a Tractor Housing, of which the following is a specification, reference being had to the accompanying drawings, forming a part thereof, in which

Figure 1 is a perspective view of the front and side of a tractor housing showing our new design.

Figure 2 is a side perspective view.

Figure 3 is a perspective view showing a side and rear of the tractor and

Figure 4 is a top plan view.

We claim:

The ornamental design for a tractor housing, as shown.

HENRY DREYFUSS.
THEOPHILUS BROWN.
